(57) **CLAIM**

The ornamental design for a treatment tool for medical care, as shown and described.

DESCRIPTION

FIG. 1 is a perspective view of a treatment tool for medical care.

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof; and,

FIG. 8 is a front view showing condition in which a slider is moved to distal end side thereof.

A portion for putting fingers thereon is rotatable around axis of main body.

The broken lines depict portions of the treatment tool for medical care in which the design is embodied that form no part of the claimed design.
